CLAIM

The ornamental design for a lens for image inspection camera, as shown and described.

DESCRIPTION

FIG. 1 is a front, top, and right side perspective view of a lens for image inspection camera showing my new design; FIG. 2 is a front, top, and left side perspective view thereof; FIG. 3 is a front, bottom, and left side perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

The broken lines depict portions of the lens for image inspection camera in which the design is embodied that form no part of the claimed design.
